Patented Nov. 26, 1968

212,809

STUFFED TOY

Terrance R. Mitchell, 10101 Lyndale Ave. S.,
Bloomington, Minn. 55420

Filed May 15, 1967, Ser. No. 7,109

Term of patent 14 years

(Cl. D34—4)

FIG. 1

FIG. 2

FIG. 3

FIG. 4

FIG. 5

FIG. 6

FIG. 1 is a front facing view of the stuffed toy showing my new design;

FIG. 2 is a left side view of the stuffed toy shown in FIG. 1;

FIG. 3 is a top view of the stuffed toy shown in FIG. 1;

FIG. 4 is a bottom view of the stuffed toy shown in FIG. 1;

FIG. 5 is a rear view of the stuffed toy shown in FIG. 1; and

FIG. 6 is a perspective view of the stuffed toy as viewed from the left front.

The right side view of my new design is substantially a mirror image of the view shown in FIG. 2.

I claim:

The ornamental design for a stuffed toy, as shown and described.
